US00D986554S

(12) **United States Design Patent** (10) **Patent No.:** **US D986,554 S**
(45) **Date of Patent:** **** May 23, 2023**

(54) **SHOE MIDSOLE PERIPHERY**

(71) Applicant: **Skechers U.S.A., Inc. II**, Manhattan Beach, CA (US)

(72) Inventor: **Glen Chang**, Rancho Palos Verde, CA (US)

(73) Assignee: **Skechers U.S.A., Inc. II**, Manhattan Beach, CA (US)

(**) Term: **15 Years**

(21) Appl. No.: **29/808,466**

(22) Filed: **Sep. 20, 2021**

Related U.S. Application Data

(62) Division of application No. 29/776,813, filed on Apr. 1, 2021, now Pat. No. Des. 936,345.

(57) **CLAIM**

The ornamental design for a shoe midsole periphery, as shown and described.

DESCRIPTION

FIG. 1 is a perspective view of a shoe midsole periphery in accordance with my new design; and,

FIG. 2 is a left side elevation view thereof.

The broken lines shown in the drawings represent portions of the shoe midsole periphery that form no part of the claimed design.
